Attorney

UNITED STATES PATENT OFFICE.

GRACE COOPER (NOW BY MARRIAGE GRACE COOPER NORTH), OF NEW YORK, N. Y.

BRASSIÈRE.

Application filed October 16, 1920. Serial No. 417,360.

To all whom it may concern:

Be it known that I, GRACE COOPER, a citizen of the United States, residing in the borough of Manhattan, in the city and county of New York and State of New York, have invented certain new and useful Improvements in Brassières, of which the following is a specification.

My invention relates to brassières adapted for use independently or as corset covers.

The essential objects of my invention are to attain the ends commonly sought in such garments by a single unseamed piece of cloth without closures in either the front or back whereby the bust is firmly held without impairing ability to breathe comfortably, the lines and shape of the bust effectively indicated, the straps affected to cling to the shoulders and maintain the bust down and back, and the expense of manufacture reduced to a minimum. Other objects and advantages are comfort, neatness of appearance, the elimination of auxiliary coverings, and the absence of folds.

To the above enumerated ends essentially my invention consists in such parts and in such combinations of parts as fall within the scope of the appended claim.

In the accompanying drawings which form a part of this specification—

Figure 1 is a front perspective view of my novel garment applied to the wearer.

Figure 2, a pattern of same, and

Figure 3, a fragmentary side view of the garment showing a modified form of fastening.

Like reference characters indicate like parts throughout the views.

In the form of my invention herein illustrated the garment comprises in pattern form a single piece of suitable cloth fabric comprising a substantially rectangular bust member 5 preferably slightly tapering towards its end, a back member 7, tapering towards its end a greater degree than the bust member, and parallel connecting webs or straps 9 integral with the bust and back members at intermediate portions of the adjacent ends of said members where the latter are of maximum breadth. The described parts have a peripheral binding 11 as well as a binding 12 around the neck opening 13.

In this instance the lateral edges or mar-

gins 15 of the bust member 5 are provided with series of metal eyelets 16, and the corresponding portions 18 of the back member have similarly disposed series of eyelets 19.

When applied to the wearer's body the members 5 and 7 embrace the front and back respectively as well as the sides. At points 60 below the arms the edges 15 and 18 are brought adjacent each other at one side of the body, and the two other edges 15 and 18 are adjacent each other at the other side of the body.

The members of each pair of adjacent edges are drawn together and retained in the present instance by a string lace 21 threaded crosswise through the openings 16 and 19 and knotted at the waistline 22 as at 23.

For the described fastening may be substituted that shown in Figure 3 consisting of a series of hooks 25 on one margin 18 engageable with a series of eyes 26 on the other margin 15.

The described means of fastening are not exclusive, and it will be understood that when hooks are employed a plurality of parallel rows of eyes may be used to accommodate bodies of different circumferential dimensions.

By making the body portion of the brassière with tapered ends, and with one end tapered to a greater degree than the other I am enabled to obtain a better fitting garment, which will readily accommodate itself to the bust of the wearer and obtain a better shape.

I claim:

A brassière comprising front, rear and shoulder portions forming an elongated neck opening therebetween, the front and rear portions extended laterally beyond the shoulder portions into substantial juxtaposition to form an arm opening and the side edges of each of said front and rear portions converging in a direction away from the neck opening, and means for securing said converging edges, said securing means including parts extending beyond both of said edges, whereby the said juxtaposed edges are held in substantially a common plane.

In testimony whereof I have affixed my signature.

GRACE COOPER.
